(57) CLAIM

The ornamental design for a dressing mirror, as shown and described.

DESCRIPTION

FIG. 1 is a front view of a dressing mirror showing my new design;

FIG. 2 is a rear view of the dressing mirror of FIG. 1;

FIG. 3 is a left side view of the dressing mirror of FIG. 1;

FIG. 4 is a right side view of the dressing mirror of FIG. 1;

FIG. 5 is a top view of the dressing mirror of FIG. 1;

FIG. 6 is a bottom view of the dressing mirror of FIG. 1;

FIG. 7 is a perspective view of the dressing mirror of FIG. 1;

FIG. 8 is an enlarged view of FIG. 5; and,

FIG. 9 is a partial enlarged view of portion A in FIG. 5.

Dressing mirror has a storage basket under a mirror, and the storage basket has knitting patterns. The broken lines shown in the drawings are for the purpose of illustrating portions of the dressing mirror which form no part of the claimed design.
